Johan Emil Hillebrandt INVENTOR

Frank M. Shibley BY ATTORNEY

UNITED STATES PATENT OFFICE.

JOHAN EMIL HILLEBRANDT, OF WEST BRIGHTON, NEW YORK.

MUSICAL INSTRUMENT.

Application filed June 30, 1925. Serial No. 43 504.

My invention relates to musical instruments and the object of my invention is to provide an instrument of the stringed type, such as a violin, banjo or guitar etc. of novel construction, and having a resonator of novel construction which may be made of any suitable material such as wood or metal.

In the drawings illustrating my invention, and which form a part of these specifications, I show a violin construction in which practically all the parts except the finger-board and head, are made of sheet metal such as brass or aluminum, but it will be understood that the resonator may be made of wood if desired.

Referring to the drawings;

Fig. 1 is a plan view of an instrument embodying my invention.

Fig. 2 is a side view thereof.

Fig. 3 is a longitudinal sectional plan view through the resonator.

Fig. 4 is a cross sectional view on line 4—4 of Figure 1, looking in the direction indicated by the arrows.

Fig. 5 is a cross sectional view on line 5—5 of Figure 1, looking in the direction indicated by the arrows.

The resonator, the outer wall of which is indicated by A, is made quite rigid by reason of its construction and produces musical tones of great power.

It comprises the outer tapering cylindrical wall A, and the inner tapering tubular shaped wall B, connected together along the entire length of the wall B, by the upper edges thereof along the two seams C and C' respectively, said seams comprising the upper edge portions of the elements A and B, and the side edge portions of the centre strip D, which strip extends the entire length of the resonator and forms a part of the outer wall thereof and which may be made thicker and stronger than the wall B or A. The form of the seams C and C' is clearly shown in cross section in Figures 4 and 5, and in the event that the inner wall B should be dispensed with, the seams would still be formed to provide the necessary stiffness for the outer wall, and to serve as base portions or ribs to which the braces holding the rest-bar could be attached by rivets E, used to secure the parts together. The seams may be soldered or brazed or held together in any other proper manner.

The two walls are also connected together

by vertically extending bolts or braces F—F respectively which not only brace and hold the walls in position but also renders the tones produced more smooth and uniform. It will be observed that the body of air or cubic content thereof between the walls in the space A' is substantially equal to the volume in the space B', thus supplementing each other in their resonating action. The small end of the resonator wall A, is closed by a thin inclined plate A² whereas the small end of the wall B is left open and spaced a short distance from the plate A², and terminates a short distance from the open large end of the wall A.

Firmly secured to the seams C and C' which serve as bass-bars to the resonator elements A and B, is a strip of metal G, hereinafter referred to as the bridge-base, which is made of resilient metal and extends across and above the rest-bar H, and is connected therewith by a short metal rod I, by means of which the bridge-base may be braced and its top adjusted transversely relative to the rest-bar. A bridge J is mounted on the bridge-base. The rest-bar H is herein shown as a metal tube but it may be simply an arched strip of stiff metal or of wood, and is provided with a shoulder-rest K at one end and supports the neck L and finger-board M etc., at the other end. The rest-bar and neck is disposed at an angle to the centre line through the resonator and above the same as illustrated in Figure 2, and firmly connected to the seams C and C' by braces N which extend from said seams to a brace strip O, which in turn is rigidly connected to the rest-bar.

A brace strip P is connected rigidly to the seams C and C' and supports a brace portion O' which is rigidly connected to the rest-bar. The tail-piece Q is held at its rear end by a link R to the rest K, and its sides are held by brace rods S connected to the seams C and C', and serve to hold the tail-piece well below the top of the bridge J.

The strings T extend from the tail-piece to the keys U in the usual manner.

It will be understood from the foregoing description that the violin type of bridge and fingerboard shown herein may be used, for use as a violin, and also that a banjo bridge and fingerboard may be easily substituted and the resonator and parts would constitute a banjo type of instrument, etc.

The instrument may be made in various sizes and with many modifications as to details of construction without departing from the invention disclosed.

Having thus described my invention, I claim as new:

1. A resonator for stringed musical instruments and the like comprising an outer wall and an inner tapering spaced wall, said outer and inner walls being split and the adjacent edges joined together along one side throughout the entire length and a center strip connecting said joined walls forming a support.

2. A resonator for stringed musical instruments and the like comprising an outer wall and an inner tapering wall spaced from the outer wall, said outer and inner walls being split and the adjacent edges joined together by rigid seams and a center strip connecting said seams throughout the length thereof forming a reinforced support.

3. A resonator for stringed musical instruments and the like comprising an outer wall and an inner tapering wall spaced from the outer wall, said outer and inner walls being split and the adjacent edges joined together by rigid seams extending throughout the length thereof, one end of said outer wall being closed and the corresponding end of the inner wall open and a center strip connecting said seams and forming therewith a rigid support.

4. A resonator for stringed musical instruments and the like comprising an outer wall and an inner tapering wall spaced from the outer wall, said outer and inner walls being split and the adjacent edges joined together by rigid seams extending throughout the length thereof, a center strip connecting said seams and brace rods connecting the lower sides of said walls forming a rigid support.

5. A resonator for stringed musical instruments and the like comprising an outer wall and an inner tapering wall spaced from the outer wall producing inner and outer substantially equal resonating chambers, said outer and inner walls being split and the adjacent edges joined together by longi-

tudinally extending seams and a central connecting strip forming a rigid support.

6. A resonator for stringed musical instruments and the like comprising an outer 65 tapering tubular wall and an inner spaced tubular wall, said outer and inner walls being split and the adjacent edges joined together by reenforcing seams and a center strip and forming an inner and outer sound chamber, one end of the outer wall being closed and the corresponding end of the inner wall being open and brace rods connecting the lower sides of said walls and forming with said seams a rigid support. 65

7. A resonator for stringed musical instruments and the like comprising an outer tapering tubular wall and an inner spaced tubular wall, said outer and inner walls being split and the adjacent edges joined together by longitudinally extending reenforcing seams and a center strip forming concentric resonating chambers of substantially the same capacity, one end of the outer wall being closed by an inclined plate and the 75 corresponding end of the inner wall being open and a bridge base secured to said seams and forming therewith a rigid support. 70

8. A resonator for stringed musical instruments and the like comprising an outer tapering tubular wall and an inner spaced tubular wall, said outer and inner walls being split and the adjacent edges joined together by longitudinally extending reenforcing seams and a center strip, the sides of said walls overlapping said seams, said walls forming two concentric resonating chambers of substantially the same capacity, one end of the outer chamber being closed by an inclined wall and the corresponding end of the inner chamber being open and in communication with the outer chamber, brace rods connecting the lower sides of said walls and a bridge brace connected to 85 the seams and forming therewith a rigid support. 90

In testimony whereof, I, JOHAN EMIL HILLEBRANDT, have signed my name to this specification this 15th day of June, 1925.

JOHAN EMIL HILLEBRANDT.
